UNITED STATES PATENT OFFICE.

GEORGE BUTTRESS, OF LOS ANGELES, CALIFORNIA, ASSIGNOR TO AMERICAN HOLDING COMPANY, OF LOS ANGELES, CALIFORNIA, A CORPORATION OF CALIFORNIA.

STREET-INDICATOR FOR CARS.

1,153,421.

Specification of Letters Patent. Patented Sept. 14, 1915.

Application filed April 18, 1913. Serial No. 762,092.

To all whom it may concern:

Be it known that I, GEORGE BUTTRESS, a citizen of the United States, residing at Los Angeles, in the county of Los Angeles and 5 State of California, have invented a certain new and useful Improvement in Street-Indicators for Cars, of which the following is a specification.

My invention relates to an indicator and 10 more particularly to an indicating device for street cars, an object of the invention being to provide a simple arrangement for accurately indicating streets regardless of the variations in the length of blocks. 15 Other objects will appear from the following specification, in connection with the accompanying drawings, in which,

Figure 1, is a fragmentary sectional side elevation of a car, showing my invention as 20 applied, the section being taken on lines 1—1, Fig. 2. Fig. 2, is a transverse section on lines 2—2, Fig. 1, looking in the direction of the arrow and showing the operating cables or lines, and the indicating apparatus 25 mounted in a car. Fig. 3, is an enlarged section on lines 3—3, Fig. 2. Fig. 4, is an enlarged sectional elevation on lines 4—4, Fig. 3. Fig. 5, is an enlarged sectional detail of the wheel for controlling the operation 30 of the indicator, the section being taken on lines 5—5, Fig. 6. Fig. 6, is a vertical section on lines 6—6, Fig. 5. Fig. 7, is a horizontal section on lines 7—7, Fig. 5; and Fig. 8, is a fragmentary side elevation 35 showing the indicating band, the spools on which same is wound and a means for removably holding the shaft of one of the spools in place.

Referring to the drawings, 1 designates 40 the fragment of a car, in the most advantageous place of which may be positioned a box 2, containing the operating mechanism for a band or tape 3, on which are printed, or otherwise fixed, the names and numbers 45 of streets, such names and numbers being visible through a transparent plate 4, mounted in the cover 5, hingedly secured to the box 2.

The street names and numbers-containing 50 tape or band 3, is wound on spools 6 and 7 respectively, mounted on shafts 8 and 9,

which are journaled in suitable supports 10 and 11. On said shafts 8 and 9, are keyed ratchet wheels 12 and 13, arranged to be rotated by pawls 14 and 15, pivoted on the 55 end of arms 16 and 17, loosely mounted on said shafts 8 and 9, said arms being held in normally retracted position, as illustrated in Fig. 4, by springs 18, which hold said arms 16 and 17, in engagement with stops 60 19, provided on the casing. Said pawls 14 and 15, are forced into engagement with the ratchet teeth of the wheels 12 and 13, by suitable springs 20 and 21, attached to the said arms 16 and 17. 65

The respective arms 16 and 17 are operated by means to be presently described, and it is obvious that when the ratchet wheel 12 is rotated by the pawl 14, the band 3 will also cause a rotation of the ratchet wheel 13. 70 Therefore, the pawl 15 on the arm 17 must be held free of the teeth of the ratchet wheel 13, and this is accomplished by lip 22 which extends downwardly from a horizontally disposed bracket 23 mounted on the casing. 75 The spring 21 holds the pawl 15 in engagement with said lip 22, and, when the arm 17 is drawn back to normal position by the spring 18, the said pawl 15 will be clear of the teeth of the ratchet wheel 13; when 80 drawn forward, the pawl 15 will engage the ratchet wheel 13 and move it in the direction of the arrow for a distance of one tooth. A similar lip 24, extending upwardly from the bracket 23', is provided to hold 85 the pawl 14 out of engagement with the teeth of the ratchet wheel 12, when it is revolved by the tape 3, through the medium of the positively actuated ratchet wheel 13. These lips 22 and 24, are provided primarily 90 to hold said pawls 14 and 15 when retracted out of engagement with said ratchet wheels 12 and 13, in order that such ratchet wheels may be moved independently of said pawls. When it is desired to render the ratchet 95 wheels 12 and 13, absolutely independent of the pawls 14 and 15, suitable plates 25 and 26 are interposed between the said pawls and the ratchet wheels, whereby, when the pawls are actuated by the movement of the 100 arms 16 and 17, they slide on said plates 25 and 26 without causing any movement of

the ratchet wheels. These plates 25 and 26 form integral parts of arms 27 and 28, which are loosely and laterally slidably mounted on the shafts 8 and 9, respectively. In order to maintain a proper tension on the band 3 and to constantly hold it taut, springs 29 and 30 are provided, these springs bearing against the outer peripheries of the ratchet wheels 12 and 13. The shaft 8 may be formed of two parts and coupled together in the manner shown in Fig. 3, in order that the spool 6 may be removed without disturbing the operating mechanism, and for this purpose the ends of the supports 10 and 11 are held closed by blocks 31 and 32, mounted on flat springs 33 and 34, which are connected to the casing. The shafts 8 and 9 are mounted in bearings 35 and 36, respectively, and the ends of the same which project outside of the casing may be furnished with knurled nuts 37 and 38 for manual operation of the tape 3. The arms 16 and 17 are operated by ropes or cables 39 and 40, running over rollers 41 and 42, either in the manner shown or in any other convenient manner, said ropes or cables 39 and 40 respectively, being connected to levers 43 and 44, pivotally mounted on a bifurcation 45, the free ends of which extend directly in the path of lugs or pins 46 and 47, disposed in and projecting laterally and on opposite sides from a wheel 48, which is journaled in suitable boxings 49, slidably mounted in guideways 50, provided in the respective arms of the bifurcations 45 and normally under the tension of helical springs 51, which are provided to insure at all times perfect contact of the wheel 48, with the track 52, on which it is arranged to roll. The aforementioned pins 46 and 47, are severally provided with heads 53, against which helical springs 54, are adapted to bear to hold said pins projected. The levers 43 and 44 are beveled at their lower ends, as seen at A, said levers being disposed on opposite sides of said wheel 48, with their narrow edges toward each other, as seen in Figs. 5 and 7, in order that, the pins 47 and 46 will operate said levers 43 and 44 only when they engage the thick side of said levers. It is obvious that when one of the pins engages and positively actuates one of the levers, the other pin, engaging the beveled edge of the other lever, will be depressed thereby and glide past it without effecting a change in its position. In this manner the operation of the street-indicating band is accomplished by either a forward or backward movement of the car. The aforementioned bifurcation 45 is provided with a flange 55, which is arranged to be bolted or otherwise fastened onto a member of a truck 56; however this specific mounting of the track-engaging wheel and its complementary bifurcation is immaterial.

When marking the band 3, with the street indications, the car is run from street to street and the names and numbers placed on the band at such points where the particular street ends, whereby the names and numbers of the streets will appear consecutively and accurately and remain in view for a certain length of time, regardless of the variation in the length of the blocks.

The spacing of the street names or characters on the band in Fig. 3, is illustrative only of the general arrangement. It is obvious that such spacing will vary according to the different street lengths.

What I claim, is:

1. The combination with a plurality of spools, of an indicating band wound on said spools, shafts on which said spools are mounted, ratchet wheels keyed to said shafts, arms loose on said shafts, pawls on said arms arranged for engagement with said ratchet wheels, a track engaging wheel having on each side a laterally projecting pin, springs to hold said pins projected, a lever on each side of said wheel having beveled edges disposed toward each other, said levers being in the path of said pins whereby only one of said levers is operated by the movement of the car in one direction, and cables connecting the levers and arms. 95

2. In a street car indicator, the combination with two spools, of an indicating band wound on said spools and shafts on which said spools are mounted, of ratchet wheels keyed on said shafts, arms loose on said shafts and provided with pawls for engagement with said ratchet wheels, springs to normally hold said arms retracted, means to hold said pawls out of engagement with said ratchet wheels when said arms are in retracted position, cables to operate said arms, a track engaging wheel having on each side a pin, a yielding means to hold said pins projected, and a lever disposed on each side of said wheel and in the path of said pins, said levers having beveled edges disposed toward each other, and said cables being attached to and operated by said levers. 100

3. In a street car indicator, the combination with two spools of an indicating band wound on said spools, and shafts on which said spools are mounted, of ratchet wheels keyed on said shafts, arms loose on said shafts, pawls on said arms arranged for engagement with said ratchet wheels, springs to hold said arms normally retracted, lips to hold said pawls out of engagement with said ratchet wheels when said arms are in retracted position, plates on said shafts and slidably between said pawls and ratchet wheels to prevent engagement of said pawls with said ratchet wheels, a track engaging wheel having on each side a pin, a yielding means to hold said pins projected, a lever 115

on each side of said wheel and in the path of said pins, said levers having beveled edges disposed toward each other whereby one of said levers will be operated by said 5 pins while the other lever remains stationary, and cables connecting said arms and levers.

In testimony whereof I affix my signature in the presence of two witnesses.

GEORGE BUTTRESS.
